FOREIGN PATENT DOCUMENTS

GB	2326405 A	12/1998
WO	2005097040 A1	10/2005

Primary Examiner — Brett Miller*(74) Attorney, Agent, or Firm* — Myers Bigel, P.A.(57) **CLAIM**

The ornamental design for a cover for a container, as shown and described.

DESCRIPTION

FIG. 1 is an exploded perspective view of a cover for a container showing my new design for clarity of disclosure, with environmental subject matter shown in broken line; FIG. 2 is a top perspective view thereof; FIG. 3 is a bottom perspective view thereof; FIG. 4 is a first side view thereof; FIG. 5 is a second side view thereof; FIG. 6 is a third side view thereof; FIG. 7 is a fourth side view thereof; FIG. 8 is a top view thereof; and, FIG. 9 is a bottom view thereof.

The broken lines shown depict environmental subject matter only and form no part of the claimed design.
